Atty.

UNITED STATES PATENT OFFICE.

CHARLES ALEXANDER THOMSON, OF EDINBURGH, SCOTLAND.

APPARATUS FOR HOLDING CAKES DURING THE PROCESS OF ICING.

SPECIFICATION forming part of Letters Patent No. 716,788, dated December 23, 1902.

Application filed June 26, 1902. Serial No. 113,318. (No model.)

29 all whom it may concern:

Be it known that I, CHARLES ALEXANDER THOMSON, engineer, of Gorgie Mains, Slateford road, Edinburgh, Scotland, have invented 5 certain new and useful Improvements in Apparatus for Holding Cakes During the Process of Icing, of which the following is a specification.

This invention relates to revolving stands 10 as used by confectioners and bakers for placing cakes and such like on during the process of icing and ornamentation, and has for its object to improve the construction, and thereby increase the utility, of said revolving 15 stands.

This apparatus made in accordance with 20 my invention admits of the cakes being safely and easily manipulated by its means, so that it is possible for the operator to have the cake set in position for icing top upward, edge upward, or bottom upward, as he may desire. Thus a higher class of work may be done more easily and in less time by means 25 of this invention than with the ordinary icing- stands hitherto made.

In order that my invention may be properly understood and readily carried into effect, I have hereunto appended one sheet of drawings, of which—

30 Figure 1 is a side elevation of the apparatus. Fig. 2 is a sectional plan through lines K L drawn through Fig. 1. Fig. 3 is a front view section through lines G H drawn through Fig. 1.

35 In carrying my invention into effect I construct a frame A of iron or other suitable material, preferably malleable cast-iron. The frame A supports a turn-table B at the end of its arm a. A movable arm a' swings on a 40 stalk or pin a². This stalk or pin a² may be cast on the frame A or may be made separately of mild steel or wrought-iron, or other suitable metal and fixed to frame A by being screwed into it or otherwise.

45 The aforementioned arm a' is bored at the end to receive a rod c, to which is attached a turn-table C, whose position may be altered by raising or lowering the rod c, which is held in the desired position by the screw a³ or 50 other convenient means.

The aforementioned frame A, with the movable arm, adjustable rod, and turn-tables, is

mounted on a pivot d of the adjustable boss D and may be revolved around the pivot d and fixed in any position around the pivot by 55 means of the screw a⁴ or otherwise.

Four of the most useful positions for the frame are given by holes bored in the aforementioned pivot d, and the frame A is automatically set to any one of these positions by 60 allowing a spring-bolt a⁴ to enter any one of holes.

On the aforesaid movable arm a' a plate with projection a⁶ forms a stop against another plate a⁸, which is cast on the frame A. 65 This admits of the turn-tables being brought to the same center line instantly. The movable arm a' is kept in this position by a bolt a⁷ entering a hole in the aforesaid plate a⁸.

In order that the cakes may be properly 70 sustained between the aforesaid turn-tables when set edge upward, detachable disks having four or more flat blades extending upward at right angles to them are attached to either or both turn-tables by means of small 75 spring-bolt b entering a perforated lug on bladed disk M, as indicated in Fig. 1.

Detachable plain disks of various diameters to suit different sizes of cakes are also employed, either in conjunction with or without 80 the aforesaid bladed disks.

I claim—

1. In apparatus for manipulating cakes during the process of sugar-icing or ornamentation the combination of a frame having two 85 arms with two turn-tables facing each other and in the same center line, the said frame being mounted on a horizontal pivot so that it may be revolved in a vertical plane, thus admitting of the cakes being instantly set in 90 position top upward, edge upward, or bottom upward as desired, substantially as and for the purposes hereinbefore described and illustrated on the accompanying sheet of drawings.

2. In apparatus for manipulating cakes 95 during the process of sugar-icing or ornamentation, the combination of a frame mounted on a horizontal pivot, and having two arms, with a turn-table supported by each, one arm being swung on a stalk or pin of the said 100 frame, and fitted with means whereby the turn-table which it supports may be instantly brought facing opposite to and in the same center line with the turn-table which is sup-

ported by the other arm, substantially as and for the purposes hereinbefore described and illustrated on the accompanying sheet of drawings.

5 3. In an apparatus of the character described, the combination with a revoluble frame, an adjustable and a fixed arm extending from the frame, a turn-table secured to one of said fixed arms, a rod having a socket and adjustably secured to the adjustable arm and a turn-table secured in the socket of said rod, detachable disks secured to said turn-tables constructed to hold a cake in position on said tables.

15 4. In an apparatus of the character described, the combination with a revoluble

frame, an adjustable and a fixed arm extending from the frame, a turn-table secured to one of said fixed arms, a rod having a socket and adjustably secured to the adjustable arm ²⁰ and a turn-table secured in the socket of said rod, detachable disks secured to one or both of said tables, and guards projecting upward at a right angle from the face of said disks to hold a cake against displacement. ²⁵

In testimony whereof I have hereunto affixed my signature in presence of two witnesses.

CHARLES ALEXANDER THOMSON.
